UNITED STATES PATENT OFFICE

FRANK E. LICHTENTHAELER, OF NEWTON HIGHLANDS, MASSACHUSETTS

DISTILLATION APPARATUS AND THE LIKE

Application filed September 21, 1927. Serial No. 221,062.

The present invention relates to improvements in apparatus for distillation, or the like, by which I mean to include absorbing, condensing, dissolving or chemically combining vapor bearing air or other gas, on the one hand, and a liquid, on the other hand.

The efficiency of distillation columns depends upon the completeness of the heat interchange, which in turn is dependent upon the intimacy of contact between counter flowing currents of vapor and liquid. Likewise the efficiency of absorption apparatus depends upon the intimacy of contact of an ascending stream of vapor and a descending stream of liquid absorbing agent. My invention contemplates improving the efficiency of such columns by securing a more uniform intermixture in successive stages of the opposing streams of vapor and liquid than has been heretofore possible.

In operating contact towers a system of decks and seals has been employed to retard the flow of liquid in order to bring in the time element most favorable for an interchange equilibrium. In this manner progressive stages of interchange are accomplished and the time of contact is made controllable by trapping the requisite amount of liquid at the respective decks. The liquid flows from deck to deck through sealed conductors or overflow pipes and the vapor or gas is caused to bubble through the entrapped liquid by means of vapor seals known as bubble caps. By thus trapping the liquid the disparity of the liquid volume as compared to vapor or gas volume is overcome. The requisite contact for favorable interchange is thus made possible no matter how small the liquid volume.

The passage of vapor or gas through the entrapped liquid on horizontal decks by means of perforations or passages in the decks offers the advantage of most economical use of tower cross sections. However, the desired minimum depth of liquid on the decks has not heretofore been a practical operating condition especially in the case of towers of large diameter. The level of the respective decks cannot be accurately established and the greater the diameter of the tower the greater the inaccuracy of the deck level so

that a considerable depth of liquid must be maintained on perforated decks to insure a sufficient liquid seal at all points. For example, the limitations of tower construction are such that it has not been possible to maintain as little depth as one half inch over decks of diameters now commonly employed. A liquid depth of approximately four inches is commonly required and this creates a back pressure often unfavorable and in the case of vacuum distillation destructive to the object sought. In fact the size of towers now being designed is unfavorably restricted by the mechanical difficulties of leveling the decks.

My invention is based on the observed fact that in distillation columns of standard construction the efficiency of interchange decreases per deck as the diameter of the column increases, whereas in single cap columns of small diameter full efficiency is maintained. This may be due to the fact that multiple cap columns handle the vapor in parallel streams while the liquid in a single stream contacts with the vapor stream in series fashion. At any given deck the rising vapor is of uniform composition but the liquid changes in its composition as it flows across the deck and consequently it may reach a condition of equilibrium of exchange before all the caps are supplied.

In one of its aspects, therefore, my invention consists in securing high efficiency in distillation columns or the like by dividing the descending liquid into separate parallel streams and subjecting each stream to the interaction of the ascending counter-flowing vapor. In this way the descending liquid streams are caused to parallel the ascending vapor streams. One manner of reaching this result is by supplying a liquid conductor or overflow pipe for each cap.

These and other features of the invention, including a novel and efficient form of cap by the use of which the advantages hereinabove set forth may be secured, will be best understood and appreciated from the following description of a distillation column fitted with a preferred embodiment of the cap. This has been selected for purposes of illus-

tration and shown in the accompanying drawings, in which

Fig. 1 is a sectional view of a portion of a distillation column showing a part of two decks equipped with caps.

Fig. 2 is a fragmentary view illustrating the construction of the contact deck of the cap and

Figs. 3 and 4 are fragmentary views illustrating alternative constructions of the cap deck.

The body of the column 10 is made of sheet steel and is provided with a series of horizontal sheet steel decks 12 riveted in place. Each cap comprises a complete, unitary, liquid sealed overflow and contact device and each vertical pair of caps cooperate in such manner as to furnish four liquid sealed contact areas or cap decks. The caps are herein shown as circular in cross section but they may be hexagonal or any other appropriate shape, so long as their general construction is such that they may be assembled in a compact arrangement in the decks of the column.

Each cap comprises an upright dam 14 having a serrated upper edge which by its height above the deck determines the depth of the liquid seal. Concentrically disposed with respect to the dam 14 and secured in place by bolts 26 is an inverted cap member 16 having a shallow dam 18 and a slotted contact area 20. A liquid conductor or overflow pipe 24 drains the contact area 20 being provided with a circular dam 22 at its upper end to form a seal. The dam 22 is slotted to weaken the surface film and better distribute the flow of liquid from the contact area under the small head. It will be understood that the liquid upon the contact deck or area 20 is kept in a continual turmoil by the ascending vapor. On this account and on account of the vapor pressure in the slots, the liquid remains upon the deck. The inward flow of the liquid toward the dam 22 is interrupted by the vapor passing through it and it has been found in practice that a perforated dam is all that is required to maintain the small head of liquid desire over the contact area. Concentrically arranged within the cap members is a vapor riser 28 secured in place by legs 30 attached to the contact surface of the contact area 20 and having a flaring apron 32 which deflects liquid flowing over the sealing dam 14 outwardly behind the flange or dam 18 of the cap member 16. The vapor riser extends upwardly through the dam 14 and in near proximity to the curved baffle plate 48 by which vapor passing up through the riser is deflected outwardly.

Each device comprises also a cap member 40 having an exterior contact area 44 and being secured in place by legs 42 with its lower edge disposed below the plane of the dam 14 thus completing a liquid seal for

the deck about each dam. The contact area 44 has a peripheral dam 45 and is slotted radially as shown more clearly in Fig. 2. It is provided centrally with a sealing chamber 46 of which the baffle plate 48 constitutes the bottom. The liquid conductor or overflow pipe 24 of the cap in the next higher deck extends into the sealing chamber 46 to a point below its serrated annular wall.

The lower surface of the baffle plate 48 is given the compound curvature best suited to baffle and interrupt entrained liquid in the vapor stream. It acts to collect the drops of liquid impinging upon its surface and discharge the liquid in appreciable volume from its convex center.

Fig. 3 illustrates an alternative form of contact area 54 in which perforations 56 are provided within the marginal flange 55. Fig. 4 illustrates still another modification of the contact area in which divergent surfaces 64 are provided for conducting the liquid to the slots within the marginal flange 65 of the deck. Other shapes and arrangements of slots and perforations could obviously be used within the scope of my invention.

In operating a tower such as that above described the liquid from each deck overflows at the serrated edge of the dam 14 and then flows over the dam 18 upon the interior contact area 20 on its way to the liquid conductor or overflow pipe 24. Vapor meanwhile bubbles up through the slots or perforations in the contact area 20, the depth of the liquid through which the vapor must be made to bubble being determined in part by the height of the flange or dam 22. The liquid passing down the conductor 24 is trapped by the wall 46 of the liquid seal chamber and flows out over the serrated edge of the wall upon the exterior contact area 44. The ascending stream of vapor is directed to the deck 44 by the vapor riser 28 and is dispersed when reaching it by the baffle plate 48 as already explained. The height of the dam 45 determines the depth of the liquid through which the vapor must bubble at this deck. Some liquid may leak through the contact area 44 of the cap but this is prevented from entering the vapor riser by the baffle plate 48 and falls either outside of the sealing flange 14 or inside the sealing flange 14 where it will be deflected by the apron 32 into the collecting basin formed in the lower cap element by the dam 18. Any excess of vapor or gas may pass out under the edge of the cap member 40 without causing undue back pressure, and the space outside the vapor riser 28 affords also possible relief in this respect.

From the foregoing description it will be noted that interchange is effected efficiently on account of the separate and individual liquid supply to each cap, which comprises

an aliquot part of the total liquid stream, the fraction corresponding to the number of caps. Fresh liquid is thus delivered to each of the vapor or gas and liquid contact area. Moreover the use of the space above the vapor riser for contact with the liquid saves column cross sectional area. The arrangement of the contact devices so that they work in parallel obviates the necessity of the space between the 10 caps for liquid flow. The caps can therefore be placed close together as is mechanically convenient allowing only for down flow of the liquid, thus still further economizing sectional area of the column.

15 It will also be observed that in using the novel caps of my invention twice as many areas of contact deck are secured as there are complete column decks 12; in other words, for each associated pair of caps carried by 20 two adjacent column decks, four areas of cap contact deck are provided. From this it will be apparent that the number of column decks may be reduced and appreciable savings made in the cost of column construction.

25 The deck level error is minimized by substituting a number of small cap decks independently sealed in place of a single liquid pool sealing all the caps as in present commercial construction. The shallow seals 30 made possible insure low operating pressure and minimum back pressure. This is extremely favorable for employment in vacuum distillation and for absorbing or scrubbing operations limited in respect to allowable 35 back pressure. The shallow seals moreover present the additional advantages in that the amount of liquid in process is smaller than that heretofore required in tower operations. This means less weight to support, 40 lower investment charge on material in process and quicker response to changes in adjustment.

Further a feature of safety is introduced in that excessive pressures such as might be 45 caused in high temperature operations as in petroleum distillations, by the accidental introduction of water, are quickly and freely released and dissipated without danger of bursting the tower.

50 Having thus described my invention, I claim:—

1. In a distillation column, or the like, a deck having a plurality of openings, a deck-sealing dam about each opening, a vapor riser 55 concentric with and spaced from each sealing dam, and an overflow pipe suspended beneath the vapor riser, and means for liquid sealing the end of the overflow pipe.

2. In a distillation column, or the like, a 60 deck having a plurality of dams, members cooperating with said dams to form deck seals, a vapor riser concentric with each dam, a cap having an interior surface constituting a contact area below the vapor riser and an 65 overflow pipe carried by the cap.

3. In a distillation column, or the like, a deck having a plurality of dams, a vapor riser concentric with each dam, a cap having an interior surface constituting a contact area below the vapor riser, an overflow pipe carried by the cap, and means for liquid sealing the overflow pipe. 70

4. In a distillation column, or the like, decks each having projecting above its surface a dam and a concentric vapor riser, and below its surface a concentric contact area and overflow pipe. 75

5. In a distillation column, or the like, adjacent decks with overflow openings, a perforated plate providing a contact area and a connected down-pipe carried by one deck co-operating with a second perforated plate providing a contact area and liquid seal carried by the other deck. 80

6. A bubble cap for distillation column, or the like, comprising a liquid down-pipe, a concentric vapor riser of larger diameter than the down-pipe, and a concentric cap member of greater diameter than the vapor riser carrying a liquid-sealing chamber and having an outer contact deck. 85

7. In a column for distillation purposes, or the like, a bubble cap having two perforated contact decks spaced one above the other, and a vapor riser so located as to receive vapor from the lower deck and direct it to the upper deck. 95

8. In a column for distillation purposes, or the like, a bubble cap having two spaced perforated contact decks, means for causing liquid to flow outwardly and escape from the periphery of one deck, and means for causing liquid to flow inwardly and escape from the center of the other deck. 100

9. In a distillation column, or the like, a series of decks with overflow openings, a vapor riser and plates providing two independent perforated contact areas associated with each deck opening. 105

10. In a distillation column or the like a plurality of spaced decks, adjacent decks having liquid-sealed openings therein and a liquid-sealed down pipe, and a plate associated therewith providing a liquid-covered deck area having a surface provided with vapor passages and being disposed between the decks. 110

11. In a distillation column or the like, a deck having a plurality of openings, a dam at each opening, a member cooperating with the dam to form a deck seal, an overflow pipe located beneath each opening and being liquid-sealed independently of the deck seal, and a contact area arranged to receive and expose liquid overflowing from said independent seal. 120

12. In a distillation column, or the like, superimposed decks, each deck having concentric liquid overflow and vapor openings respectively, and a cap element associated 130

with a vapor opening and forming both a liquid seal for the overflow from an upper deck and a baffle for the vapor opening, and a contact deck associated with said cap element.

5 13. In a distillation column, or the like, an overflow pipe, a cap element providing a liquid seal therefor, a perforated plate providing a contact area surrounding said seal, and means for causing vapor to pass through

10 the liquid on the contact area.

In testimony whereof I have affixed my signature.
